FILM PACK.

Application filed November 3, 1923, Serial No. 672,634, and in Germany January 13, 1923.

The invention relates to a film pack with tabs and consists of an outer sheath of pasteboard, or other similar material and an inner case of sheet metal with a continuous partition between the exposed and unexposed films. Packs having an outer paste-board sheath besides effecting substantial saving in weight as compared with packs entirely of sheet metal enable the films to be drawn more easily owing to the greater flexibility of the pasteboard walls in comparison with the rigid metal casing. In order, however, to fully utilize these advantages the individual parts of the inner metal case must also be as flexible as possible, so as to facilitate the changing of the films. At the same time, it is desirable that the case should constitute a framing for the outer casing, which is very liable to be deformed, and thus prevent it from bulging outward and thereby admitting light to the films, especially at the exposure aperture.

Film packs which fulfil one or the other of these requirements are known, but these advantages are obtained at the cost of a third requirement. Thus, for example, in a known device, the resilient flexibility of the partition is obtained by the arrangement of a second wall inclined to the first, the result being a considerable increase in weight. In another known film pack the sheet metal insertion is formed mainly by a continuous partition, which is arranged in the pasteboard casing so as to yield easily. This insertion is of slight weight and is sufficiently resilient when the clamping strips are drawn down, but it does not provide sufficient stiffening for the outer pasteboard sheath or a sufficient guide for the films at the back to prevent tearing at the projecting stops when pulled obliquely. Another known sheet insertion eliminates these disadvantages and gives the pasteboard sheath a sufficient hold, but the partition is rigid and unyielding within the casing, so that the resistance offered on changing over the film is considerably increased.

The object of the present invention is to obtain the described advantages with an outer pasteboard sheath without entailing any of the disadvantages referred to. For this purpose the central partition, which divides the pack into two approximately equal

spaces for the exposed and the unexposed films, is rigidly connected, for a part only 55 of its length, with the outer pasteboard casing by means of two lateral members which bear against the long narrow sides of the outer casing; the other parts, however, of this partition, the free end of which is 60 formed as a change over bridge for the films, are adapted to move so as to be bent out of their central plane to either side. For this purpose it is sufficient to hinge together in any simple manner the two parts of the partition at their junction. It is preferable, however, to impart resilient flexibility to the free end of the central partition, either by the arrangement of spring members or by utilizing the resilience of the sheet metal 70 partition itself.

The accompanying drawings illustrate various constructions according to the invention:

Fig. 1 represents a complete pack in longitudinal section.

Fig. 2 is a view of the sheet insertion seen from the back, the pasteboard sheath being shown in section and the contents of the pack assumed to be withdrawn. The movable end of the partition is hinged to the fixed part by means of clamps.

In Figs. 3-9 modifications of the sheet metal insertion are shown in longitudinal section, plan or in cross section.

Figs. 3 and 4 show a construction with spring connecting members between the fixed and the movable part of the partition.

Figs. 5-7 show a construction in which the central partition is made in one piece and 90 springs at its free end by its own elasticity.

Fig. 7 is a section on the line 1-1 of Fig. 6.

Figs. 8 and 9 show the construction of the elastic part of the partition in the form of 95 tongues, which at the same time press the unexposed film strips against the exposure aperture.

In Figs. 1 and 2 the films *a* with tabs *b* are stored in known manner on both sides of 100 the partition *c*₁ or *c*₂ and are inclosed light-tight by the outer sheath *d* by means of folded over strips *d*₁ of velvet.

The partition *c*₁ is connected below with a cross-piece *e* which overlaps at its front 105 surface *f* the ends of the unexposed films

and at the back has a sloping guide-surface *g* and on both sides external stops *h* to limit the motion of the withdrawn exposed films. On both sides of the partition, along the narrow sides of the pack, are arranged sheet metal members *i* (Fig. 7) with which both the cross-piece *e* and the partition *c*₁ are rigidly connected, for example by means of punched out and bent over clips *k*₁, *k*₂.

13 The movable part *c*₂ is hinged on the upper end of the fixed part *c*₁ of the partition, for example by small wire clamps *l*, which are passed through corresponding holes in both parts and then bent together. The sheet metal is hooked over at the end of the partition *c*₂ to form a change over bridge *m* over which the exposed films are withdrawn in known manner to the back of the pack. Spring tongues *n*, which press the unexposed films against the frame *o* of the outer pasteboard sheath are bent out from the partition *c*₁, *c*₂ in known manner. To save weight, openings *p* are also provided at appropriate positions in the sheet metal partition.

18 In Figs. 3 and 4 the fixed part of the partition *c*₁ is connected with the flexible part *c*₂ by very thin leaf springs *q*, which may overlap both parts for a certain distance on one side and are suitably connected therewith, for example by cutting out and bending together strips *r*.

23 A modification of the invention is shown in Figs. 5-7. The partition *c* in this case consists of a single piece and is connected with lateral members *i* at several points as shown in Fig. 7 by means of strips *k*₁, *k*₂ so as to enable the projecting end of the sheet metal partition to bend elastically 40 about the line 1-1 of Fig. 6. By shifting the line 1-1 forward or back, as well as by enlarging or reducing the openings *p* the resilience of the free end of the partition *c* may be controlled as desired.

45 Finally, in the construction shown in Figs. 8 and 9, only two strips of the flexible part of the central partition *c* are retained, through the hooked end of which a cylindrical rod *t* is passed, which serves as a change over bridge for the films. At the same time, the strips *s* are bent somewhat out of the central plane of the walls, so as to press the contents of the pack resiliently against the exposure chamber of the outer casing, thus obviating the necessity for providing particular tongues *n* for this purpose at this point. When, therefore, an exposed film is being drawn over, a tensile force *P* is exerted on the change over bridge which 50 springs in the direction of the arrow and returns to its previous position when the film is drawn over.

55 I do not wish to be understood as limiting myself to the exact details of construction heretofore described or shown in ac-

companying drawings as it is obvious that these details may be modified without departing from the general principle.

Having now described my invention what I claim is,—

70 1. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition for a part of its length being rigidly connected with the lateral members and at the end next the change over bridge being adapted to be displaced from its normal position.

75 2. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition for a part of its length being rigidly connected with the lateral members and at the end next the change over bridge being adapted to be displaced from its normal position.

80 3. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition for a part of its length being rigidly connected with the lateral members and at the end next the change over bridge being adapted to be displaced from its normal position.

85 4. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

90 5. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition for a part of its length being rigidly connected with the lateral members and at the end next the change over bridge being adapted to be displaced elastically from its normal position.

95 6. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

100 7. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

105 8. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

110 9. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

115 10. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

120 11. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

125 12. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

130 13. A film pack with tabs, consisting of an outer pasteboard casing and an inner sheet metal case including two continuous lateral members and a central partition which divides the length of the pack space in two and together with the said continuous lateral members forms an I-shaped cross-section, and at one end defines a change-over bridge, the partition comprising two portions, one of which is rigidly connected with the lateral members and the other at the end next the change over bridge being adapted to be displaced elastically from its normal position, and defining spring members deflected laterally out of the general plane of the partition.

5. In a film pack, the combination with an outer casing of a material having the character of paste board, of an inner metal case comprising a sheet metal partition disposed to divide the pack space in two parts, lateral frame members, means rigidly connecting a part of the partition to the said members so as to leave a portion of the partition free to move out of its normal position, the said portion being formed at its 10 free end to define a change-over bridge.
- In testimony whereof I affix my signature.

DR. ING. WILHELM HOHMANN.
